6 Claims. (Cl. 200—31)

The present invention relates to distributors for internal combustion engines.

As is well known, such distributors conventionally include an interruptor plate which is turnable within the housing of the distributor and which has its position determined by the extent of partial vacuum in the intake manifold of the internal combustion engine. Conventionally, such a distributor plate is acted upon by a spring which urges it to turn in a given direction in the distributor housing.

In order to provide for the best possible operation of an internal combustion engine, it is required to adapt as closely as possible the timing of the ignition in the cylinders of the internal combustion engine with the constantly changing load on the engine. For this purpose there have already been provided various devices which are capable of adjusting the timing of the ignition, and the most common of these devices operate either from a centrifugal governor or from the partial vacuum in the intake manifold of the engine or from both of these devices.

Where the position of the interruptor plate is controlled solely by the partial vacuum in the intake manifold, it is conventional to provide in the distributor housing a spring which urges the interruptor plate in a given direction, and this spring may conventionally take the form of an elongated coil spring connected to the interruptor plate so as to urge it to turn in a given direction and also connected with an adjusting screw accessible at the exterior of the housing and, for example, passing through the wall of the distributor housing. The space within the distributor housing is extremely limited and also the space in which the entire distributor may be accommodated is extremely limited, so that such an arrangement where an elongated coil spring is connected to the interruptor plate and is adjustable from the exterior of the housing provides great difficulties with respect to the mounting of the parts in the available space and in addition it is difficult to adjust such a construction so as to provide the desired influence on the distributor. Also, this known construction is quite expensive.

It is accordingly a primary object of the present invention to provide a distributor construction which will avoid the above drawbacks.

More particularly, it is an object of the present invention to provide a distributor with an extremely compact and simple structure for influencing the position of the interruptor plate within the distributor housing. Also, it is an object of the present invention to provide a structure of this type which can be easily adjusted and which also is quite inexpensive while at the same time being very reliable in operation.

With the above objects in view the invention includes, in a distributor for an internal combustion engine, a distributor housing having a portion which is stationary with respect to the housing. An interruptor plate is located in the distributor housing and carries a projection. A pivot pin is carried by the housing and extends through an opening of the interruptor plate to guide the latter for turning movement. In accordance with the present invention, a spring is carried by this pivot pin and has a pair of legs one of which engages the above-mentioned

2

portion of the housing and the other of which engages the projection of the interruptor plate to urge this projection away from the above-mentioned portion of the housing so that the spring will urge the interruptor plate to turn in a given direction in the housing. This structure of the invention is extremely simple while at the same time being very compact so that it can be very easily accommodated within the interruptor housing.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

FIG. 1 is a partly diagrammatic plan view of a distributor provided with the structure of the invention, the cover of the distributor being removed so that the interior thereof is visible in FIG. 1; and

FIG. 2 is a fragmentary sectional elevation taken along line II—II of FIG. 1 in the direction of the arrows.

Referring to the drawings, it will be seen that the distributor housing 10 accommodates in its interior an interruptor plate 11. The floor of the distributor housing carries a pivot pin 12 which extends through an opening of the interruptor plate 11 so that in this way the plate 11 is guided by the pivot pin 12 for turning movement within the housing 10. The floor of the housing 10 has a relatively thick boss portion 10' which carries the pivot 12, as is shown most clearly in FIG. 2, and the opening of the interruptor plate 11 which receives the pivot pin 12 is sprayed with nylon so as to be provided with a nylon sleeve, and this nylon sleeve has a flange portion 11' which directly engages the boss 10', as is also shown most clearly in FIG. 2.

In the illustrated position of the parts, the interruptor plate 11 is held in the illustrated position by a spring which may, for example, be made of steel wire having a diameter of 1.5 mm. The spring has a pair of legs 13 and 14, and the leg 13 engages an abutment portion of the housing 10, this housing portion being in the form of a rib which is integral with the side wall of the housing 10 and located in the interior thereof. The rib of the housing 10 is formed with an elongated depression 15 which receives the leg 13 of the spring. The other leg 14 of the spring engages a projection 16 which is carried by the interruptor plate 11, and the legs 13 and 14 tend to move apart from each other so that they urge the projection 16 away from the wall portion of the housing engaged by the leg 13, and thus the spring which is carried by the pivot pin 12 urges the interruptor plate 11 to turn in a clockwise direction about the pin 12, as viewed in FIG. 1. The projection 16 is in the form of an adjusting pin having a portion 16' turnably connected to the plate 11 and the turning axis of the pin 16 is eccentric with respect to the central axis thereof so that the pin or projection 16 is eccentrically mounted and thus turning of the pin 16 will adjust the spring by moving the leg 14 toward or away from the leg 13. In the illustrated example the legs 13 and 14 are integral with a single convolution 17 which surrounds the pivot pin 12, and in accordance with the invention the spring has at least one convolution extending around the pivot pin 12 and from which the legs 13 and 14 project.

As is apparent from the above description and the drawings the interruptor plate 11 will be held by the spring 13, 14, 17 in the illustrated position as long as it is not moved in one direction or the other by an elongated connecting rod 18 which is pivotally connected at 19 to the interruptor plate 11. This elongated connecting rod 18 is connected at its end which is distant from the

pivot 19 to a diaphragm located within the housing 20 and dividing the latter into a pair of chambers in one of which the connecting rod 18 is located. The other chamber on the other side of the diaphragm communicates through a conduit 20' and a connecting pipe 20 with the intake manifold of the engine, so that as the partial vacuum in the intake manifold changes the diaphragm in the housing 20 will move so as to move the connecting rod 18 in a manner very well known in the art, and thus the plate 11 will be turned about the pin 12 in one direction or the other to have its angular position determined by the extent of partial vacuum in the intake manifold of the internal combustion engine.

The interruptor plate 11 carries an interrupting mechanism which includes an interruptor lever 23 turnable about a pivot pin 22 carried by the plate 11 and carrying the interruptor contact 24 which cooperates with a second contact 26 carried by a contact-carrier 25. A rotary shaft 27, driven in a well known manner from the engine itself, carries the cam 28 whose camming portions engage a projection 29 carried by the interruptor lever 23, so that as the cam 28 turns with the shaft 27 the camming portions will cooperate with the projection 29 to turn the lever 23 in one direction to separate the contact 24 from the contact 26 and then to permit the lever 23 to return to the position where the contact 24 engages the contact 26. A spring 30 cooperates with the lever 23 to urge it in a counterclockwise direction, as viewed in FIG. 1, about the pin 22, so that the spring 30 acts on the lever 23 for urging the contact 24 into engagement with the contact 26, and as each camming portion of the cam 28 passes beyond the projection 29 the spring 30 will return the contact 24 into engagement with the contact 26.

A condenser 31 is electrically connected in parallel with the interruptor contacts 24 and 26, and the condenser 31 is carried by the floor of the interruptor housing 10. Finally, an electrical conductor 32 is provided for connecting the interrupter with the primary winding of an unillustrated ignition coil, and the conductor 32 passes through a rubber sleeve 32' so as to be insulated from the wall of the housing 10.

As a result of the above-described structure of the invention which includes the spring 13, 14, 17, it is possible to adapt the timing of the ignition to widely different operating requirements of different internal combustion engines in the simplest possible way, as by turning the pin 16 as well as by choosing a wire spring of proper diameter and by providing a given number of coils which surround the pin 12. Moreover, all of these requirements are satisfied with a structure which requires an extremely small amount of space, and the fact that the structure of the invention may be accommodated in an extremely small space is of great significance in distributors of the type described above and shown in the drawing.

It will be understood that each of the elements described above, or two or more together, may also find a useful application in other types of distributors differing from the types described above.

While the invention has been illustrated and described as embodied in adjustable distributors, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. In a distributor for an internal combustion engine, in combination, a distributor housing; first abutment means on said distributor housing; an interruptor plate in said housing; second abutment means carried by said interruptor plate; a pivot pin carried by said housing and extending through an opening of said plate to guide the latter for turning movement in said housing; and a spring carried by said pivot pin and having a pair of legs one of which engages said first abutment means of said housing and the other of which engages said second abutment means on said plate for urging said projection away from said portion of said housing, so that said spring urges said plate to turn in a given direction with respect to said pin, one of said abutment means being adjustable in a direction transverse to the respective leg to adjust the force with which said spring urges said plate to turn in said direction.

2. In a distributor for an internal combustion engine, in combination, a distributor housing having an abutment portion; an interruptor plate in said housing; a pivot pin carried by said housing and extending through an opening of said plate to guide the latter for turning movement in said housing; a pin carried by said plate turnably about an axis parallel to said pivot pin and having a projection arranged eccentrically with respect to said axis; and a wire spring carried by said pivot pin and having a pair of legs one of which engages said portion of said housing and the other of which engages said projection of said pin for urging said projection away from said portion of said housing so as to urge said plate to turn in a given direction with respect to said pivot pin.

3. In a distributor for an internal combustion engine, in combination, a distributor housing having an abutment portion which is stationary with respect to said housing; an interruptor plate located in said housing; a pivot pin carried by said housing and extending through an opening of said plate to guide the latter for turning movement; a pin carried by said plate turnably about an axis parallel to said pivot pin and having a projection arranged eccentrically with respect to said axis; and a spring carried by said pivot pin and having a pair of legs one of which engages said portion of said housing and the other of which engages said projection of said pin to urge said projection away from said portion of said housing so that said spring urges said plate to turn in a given direction with respect to said pivot pin, said spring having at least one convolution surrounding said pivot pin.

4. In a distributor for an internal combustion engine, in combination, a distributor housing having a wall portion; an interruptor plate located in said housing; a pivot pin carried by said housing and extending through an opening of said plate to guide the latter for turning movement; a pin carried by said plate turnably about an axis parallel to said pivot pin and having a projection arranged eccentrically with respect to said axis; and a spring carried by said pivot pin and having a pair of legs one of which engages said wall portion of said housing and the other of which engages said projection of said pin for urging said projection away from said portion of said housing so that said spring urges said plate to turn in a given direction with respect to said pivot pin.

5. In a distributor as recited in claim 4, said wall portion of said housing being formed with a depression which receives said one leg of said spring.

6. In a distributor for an internal combustion engine, in combination, a distributor housing having a wall carrying in the interior of said housing a rib which is formed with a depression; an interruptor plate located in said housing; a pivot pin carried by said housing and extending through an opening of said plate to guide the latter for turning movement; a pin carried by said plate turnably about an axis parallel to said pivot pin and having a projection arranged eccentrically with respect to said

axis; and a wire spring coiled about said pivot pin and having a pair of legs one of which is received in said depression and the other of which engages said projection to urge the latter away from said rib so that said spring urges said plate to turn in a given direction with respect to said pivot pin.
